(57) **CLAIM**

The ornamental design for a trocar, as shown and described.

DESCRIPTIONFIG. 1 is a perspective view of a trocar;
FIG. 2 is a right side elevational view of the trocar of FIG. 1;FIG. 3 is a left side elevational view of the trocar of FIG. 1;
FIG. 4 is a top elevational view of the trocar of FIG. 1;
FIG. 5 is a bottom elevational view of the trocar of FIG. 1;
FIG. 6 is a rear elevational view of the trocar of FIG. 1;
FIG. 7 is a front elevational view of the trocar of FIG. 1; and,
FIG. 8 is a perspective view of the trocar of FIG. 1.
The broken lines shown in FIGS. 6 and 8 depict environmental subject matter only and form no part of the claimed design.**1 Claim, 5 Drawing Sheets**(56)
